UNITED STATES PATENT OFFICE.

JOHN DARBY, OF SUMMIT, AND CLIFFORD D. MEEKER, OF ORANGE, NEW JERSEY.

LAMP-SOCKET.

1,076,026.

Specification of Letters Patent. Patented Oct. 21, 1913.

Application filed February 4, 1910. Serial No. 542,078.

To all whom it may concern:

Be it known that we, JOHN DARBY and CLIFFORD D. MEEKER, citizens of the United States, said DARBY residing in Summit, in 5 the county of Union and State of New Jersey, and said MEEKER residing at Orange, in the county of Essex and State of New Jersey, have invented certain new and useful Improvements in Lamp-Sockets, of which 10 the following is a specification.

The invention relates to electric lamp sockets and in certain of its aspects more especially to sockets having a double pole and double break control of the circuit but 15 certain features of the invention will be found useful in other kinds of sockets.

The objects of the invention will in part be obvious to those skilled in the art and will in part be found set forth hereinafter.

20 The invention consists in the novel parts, constructions, combinations and improvements herein shown and described.

The accompanying drawings, referred to herein, and forming a part hereof, illustrate 25 one embodiment of the invention, the same serving in connection with the description herein to explain the principles of the invention.

Of the drawings: Figure 1 is a side elevation 30 of a lamp socket embodying the invention with the shell removed, and the side support cut away on the line A—B of Fig. 2; Fig. 2 is a side elevation looking at Fig. 1 from the right; Fig. 3 is an elevation looking obliquely at Fig. 1 from the left and the 35 rear; Fig. 4 is a central vertical section on the line C—D of Fig. 2 looking in the direction of the arrows; Fig. 5 is a perspective view of a side support for the socket heads 40 and for one end of the controller and for the detent and pawl levers and also the pull chain bell; Fig. 6 is a detail of the detent piece and detent lever separated for the sake of clearness; Fig. 7 is a detail view of the 45 ratchet wheel its lever, the pawl and the spring connecting to the detent lever; Fig. 8 is a perspective view of the shaft of the controller; Fig. 9 embraces two perspective views of the controller pieces of insulating 50 material, one without the conducting strip mounted thereon, and the other with the conducting strip mounted thereon; Fig. 10 comprises two perspective views showing the contact piece which fits over and is carried by the controller member shown in Fig. 55 9 in two different positions; Fig. 11 is a de-

tail of the end of one form of pull chain which connects with the pawl lever; Fig. 12 is a plan view on the line E—F of Fig. 1, with the actuating means for the controller, 60 as well as certain other parts, removed for the sake of clearness; Fig. 13 is a bottom plan view corresponding to Figs. 3 and 4; Fig. 14 is a side elevation, with parts broken away, of a different arrangement of the pawl lever and detent lever and certain associated parts; Fig. 15 is a fragmentary detail in elevation of the actuating mechanism for the controller on an enlarged scale; and Fig. 16 is an elevation of a complete socket inclosed 65 in the external shell. 70

Referring to the accompanying drawings, illustrating by way of example, one embodiment of invention, a socket structure is shown of general cylindrical form and having heads 1 and 2 of insulating material and supporting means connecting the same. The form of supporting means shown consists of standards 3 and 4 set into recesses or depressions in the opposed heads 1 and 2, and suitably fastened, as by screws taking into the holes 5 and 6. 75

The socket shown in the drawings, has a double pole, double break control over the circuit, that is, each branch of the circuit is 80 broken at two points to shut off the current and each branch is made at two points to turn on the current. There are shown therefore four contact strips or brushes separated from each other in pairs. The two brushes 85 in each pair, that is, the two brushes in one branch of the circuit, are also separated from each other the circuit being made or broken between them by a conducting piece 90 on the controller which bridges the gap between them to make the circuit and to break the circuit out of contact with each brush, leaving a gap between the two contact pieces 95 or poles.

A brush 7 is shown carried on the supporting piece 8 carried by the head 1. A binding screw 9 serves to connect the brush 7 to the line. The complementary brush 10, that is, the one in the same branch of the circuit, is carried by the head 2 and connects to one of the lamp terminals 11 by the screw 12. In the other branch of the circuit is the brush or contact piece 15 carried on the supporting piece 14 fixed to the head 1, and provided with a binding screw 17 105 to connect the contact pieces with the line. The end of this brush 15 is turned back 110

as shown in Figs. 1 and 3 to get a spring wiping action in the direction of the rotation of the controller. The companion contact piece 18 is carried by the head 2 and connects by the screw 19 to the plate 20 formed on the threaded portion 21 of the shell into which the lamp screws. This contact piece has its end bent backwardly, similarly to the contact piece 17, to get the same spring wiping action in the direction of the rotation of the controller.

The controller is arranged transversely of the axis of the socket, and is rotatably mounted. It comprises as herein embodied, 15 a generally cylindrical member 25 of insulating material, and a similar member 26 at the other end thereof. Each of these members 25 and 26 is shown with a squared, or non-cylindrical, central aperture 27 into which fits the squared, or non-cylindrical, shaft 28, the shaft 28 having at its ends the pintles 29 and 30 fitting into the apertures 31 and 32 in the standards or supporting pieces 3 and 4.

25 Each of the members 25 and 26 is provided with a conducting piece numbered 35 and 36 respectively. These conducting pieces may be alike, and referring to Fig. 10 the conducting piece 35 is shown having
30 the conducting surfaces 37 and 38 with which the contacts or brushes 7 and 10 co-operate to close that branch of the circuit. These contact surfaces 37 and 38 lie along the cylindrical part of the member 25, as
35 shown in Figs. 1, 2 and 3, and have narrowed portions 39 and 40 extending therefrom along the surface of the cylindrical part and bent at right angles to fit over the edge formed by the junction of the side
40 and end of the controller cylinder and are connected together by the ring 41.

The conducting piece and the insulating cylinder on which it is carried are formed so that the conducting strip may be sprung into position thereon, and will be retained in position thereon against displacement either lengthwise of or around the cylinder. Referring now to the part 25, shown in detail in Fig. 9 there is a raised portion 42 and a corresponding portion 43 arranged diametrically opposite each other upon the circular edge joining the side and end of the cylinder. There are spaces 44 and 45 between said raised portions. Centrally of the end of the cylinder is shown the projecting hub 46. In assembling the contact surfaces 37 and 38 may be sprung slightly apart when they will pass over the projecting parts 42 and 43 on the end of the cylinder 25, and after passing may be released when they will spring together against the surface of the cylinder 25 and within the projecting parts 42 and 43. The narrow parts 39 and 40 will then lie in the recesses 44 and 45, and the ring 41 will lie in the cir-

cular depression between the projecting parts 42 and 43 and the hub 46. It will thus be seen that the conducting piece while being practically instantly placed in position, and without any bending, shaping or fastening means whatsoever, in the assembling of the parts, is held firmly and accurately in position. 70

Mounted intermediately the cylinders 25 and 26 is the actuating and controlling mechanism for the controller. The four-tooth ratchet wheel 50 is shown with the central square aperture 51, which fits on the squared shaft 28. The four-faced detent piece 52 having the squared central aperture 53 likewise is adapted to fit on the squared shaft 28 as shown in Fig. 6 of the drawings. The ratchet wheel and the detent piece are placed on the shaft intermediately the cylinder 25 and 26, and the shaft is then placed in position between the standards 3 and 4 which are fastened in position, the whole being thus rapidly and economically assembled and presenting a strong, simple, compact and accurately operating mechanism. 90

The detent lever 56 is shown having the face 57 thereon to coöperate with the detent piece, said face 57 being offset therefrom for convenience in construction. The lever 56 has a downward extending part 58 to which the spring 59 may be attached. In the upper part of the lever is shown the aperture 60 having the recesses 61 and 62 opening therefrom substantially diametrically opposite each other. The pawl lever 65 is conveniently shown of curvilinear form. This lever is shown with an aperture 66 and a transverse part 67 and 68 connecting therewith, substantially the same as those in the 100 detent lever. Carried on the lever 65 is the pawl 69 having an aperture 70, with the transverse recesses 71 and 72 communicating therewith. Struck up from the end of the lever 65 is the T-shaped projection 74. Said projections 74 and the aperture in the pawl lever constitute a pivotal bearing for the pawl upon the lever. The T-shaped projection 74 is of such a size that it will pass through the aperture 70 and the transverse 110 enlargement 71 and 72, but when these transverse enlargements or recesses 71 and 72 pass out of alinement with the head of the T-shaped projection 74, the pawl is held securely in position upon the lever while free to rotate or pivot relatively thereto, as shown in Figs. 3 and 4. When the parts are assembled in operative relation the pawl is always in a position where the head of the projection 4 holds it from displacement and disconnection from its lever 65 while allowing a free pivotal action. The spring 59 is shown engaging the projection 75 on the pawl. 115 120 125

In Fig. 1 an arm 99 extending through the 130

socket shell, and being an extension of the lever 65, and may be used to work the controller either by the finger or by having a chain attached.

5 The pawl lever and detent lever are thus carried by a common mounting eccentric to the rotatable controller. The detent lever passes to one side of the controller and engages the detent piece at the side. The 10 pawl lever passes to the other side and around the controller, the pawl engaging the ratchet wheel on the opposite side of the controller axis from the pivotal mounting for the lever. The spring connection between the levers gives a strong and positive 15 spring action for giving the detent a quick snapping action making a sharp, quick break at the contact.

Upon the standard or supporting member 20 4 is shown a part 78 extending substantially at right angles to the main part of the standard, and this part may if desired lie in a recess in the surface of the socket head. This part 78 is shown with its end 79 bent 25 downwardly and having projecting therefrom the T-shaped part 80. The detent lever 56 and the pawl lever 65 may both be mounted upon said projection in substantially the same way that the pawl 69 is 30 mounted upon the pawl lever. When these levers are swung around into operative position, the elongated portion of the apertures is out of alinement with the elongated head of the projection 80, and these levers 35 are thus securely held in position upon the member 80 as a bearing, but are free for pivotal motion, as will appear from Fig. 4.

The bell or funnel for the pull chain is carried on one of the supporting standards. 40 Extending from the part 78 of the standard 4 is shown an arm or strip 84, which may also lie in a recess in the head 1, shown with a downwardly extending part 85 having an aperture 86 therein. Fastened 45 surely on said part 86 is shown the bell or funnel 87 for the pull chain 88. The pull chain 88 has a link 89 let into the last ball, and the lever 65 is shown with an aperture 90 therein which may be cut out to the edge 50 of the lever with a straight cut without removing any of the metal. If the metal be then bent a little to one side the link 89 may be slipped thereover and the metal then straightened back into position to hold 55 the chain firmly on the lever (see Figs. 4, 7 and 11).

In Fig. 14 the pawl and detent levers are shown pivotally mounted below the controller, the detent lever passing to one side 60 and engaging the detent piece 52 at the side of the controller, the pawl lever 65 passing around the controller on the other side, and the pawl 69 engaging the ratchet wheel 50 on the opposite side of its axis from the 65 pivotal bearing 80. This enables the pull

chain to be carried at the top of the socket and for it to have also a straight line pull from the bell 87 to the end of the pawl lever 65. There is also shown in Fig. 14 as a fastening means between the chain and 70 pawl lever, a couple of prongs 92 struck up from the ends of the lever and adapted to slip in between two of the balls in the chain 88, which permits of rapid and easy assembling and yet holds the chain securely 75 in position.

In Fig. 15 is shown an enlarged view of the parts of the controller as assembled upon the shaft 28. The conducting pieces may be simply sprung into position upon the insulating cylindrical member 25 and 26, as already described, one of the cylinders may be slipped upon the shaft 28, the detent piece and the ratchet wheel may then be slipped on, followed by the other cylindrical member carrying its conducting strip. The shaft 28 may then be placed between the standards 3 and 4, the pintles 29 and 30 going into the apertures 31 and 32. The standards may already be attached to one 90 of the socket heads, and may then be quickly attached to the other. Before this is done, however, the detent lever and ratchet lever may have been mounted upon the T-shaped pivotal bearing 80. It will 95 thus be seen that the socket may be very expeditiously and economically assembled, while consisting of a very few number of parts, which are of strong construction, of very positive and certain action, and which 100 are securely held in position. The parts are also arranged to give a very large space between the four making and breaking points in the circuit whereby extraordinary currents may be carried. 105

The manner of operation of the herein described mechanism, will be clearly understood from the foregoing description.

As a brief summary it may be stated that a pull on the chain 88 will move the lever 110 65 and cause the pawl 69 to actuate the ratchet wheel 50. The movement of the lever will also put additional tension on the spring 59, and at the same time the rotatory movement of the detent piece 52 moves back 115 the detent lever, further increasing the tension on spring 59. During this time the brushes are sliding over the conducting pieces 37 and 38 on the controller, the circuit being unbroken. As the detent piece 120 52 passes over its dead center, all the pressure on the spring 59 then acts to give a sudden, snapping movement until the next face is flat against and held by the contact piece 57 on the detent lever. Just after 125 this sudden, snapping movement has begun the brushes leave their contact pieces making a quick simultaneous break at the four points in the circuit. The controller gets a quarter turn at each actuation and this 125

make successive makes and breaks of the circuit. Fig. 1 shows the controller in the break position and Fig. 4 shows it in the make position.

5 It will be understood that variations may be made from the constructions shown within the scope of the appended claims without departing from the principles of the invention.

10 What we do claim and desire to secure by Letters Patent, is:

1. A lamp socket including in combination contacts connected to the circuit, a rotatable controller for making and breaking the circuit at said contacts, a ratchet fixed to rotate with said controller, a detent piece fixed to rotate with the controller, a pawl lever and a detent lever pivotally mounted on a common mounting eccentric to said controller, one lever passing to one side of the controller and the other passing to the other side of said controller, and means for holding the detent to the detent piece and the pawl to the ratchet.

2. A lamp socket including in combination contacts connected to the circuit, a rotatable controller for making and breaking the circuit at said contacts, a ratchet fixed to rotate with said controller, a detent piece fixed to rotate with the controller, a pawl lever and a detent lever pivotally mounted on a common mounting eccentric to said controller, one lever passing to one side of the controller and the other passing to the other side of said controller, and a spring in tension between the detent lever and the pawl.

3. A lamp socket including in combination a rotatable controller arranged transversely of the axis of the socket, conducting pieces at each end of the controller, a branch of the circuit at either side of the socket having contacts coöperating with the conducting pieces on the controller to open and close the branches of the circuit, respectively, a ratchet and a detent piece fixed to rotate with the controller and located intermediately the conducting pieces, a pawl carrying lever and a detent lever having a common pivotal mounting eccentric to the controller and common means for holding the detent lever to the detent piece and the pawl to the ratchet wheel.

4. A lamp socket including in combination a rotatable controller arranged transversely of the axis of the socket, conducting pieces at each end of the controller, a branch of the circuit at either side of the socket having contacts coöperating with the conducting pieces on the controller to open and close the branches of the circuit, respectively, a ratchet and a detent piece fixed to rotate with the controller and located intermediately the conducting pieces, a pawl carrying lever and a detent lever having a com-

mon pivotal mounting eccentric to the controller, the detent lever passing to one side of the controller and the pawl carrying lever passing to the other side of the controller and a spring in tension between the 70 detent lever and the pawl.

5. A lamp socket including in combination a rotatable controller arranged transversely of the axis of the socket, conducting pieces at each end of the controller, a branch 75 of the circuit at either side of the socket having contacts coöperating with the conducting pieces on the controller to open and close the branches of the circuit, respectively, a ratchet and a detent piece fixed to rotate with the controller and located intermediately the conducting pieces, a pawl carrying lever and a detent lever having a common pivotal mounting eccentric to the controller, the detent lever passing to one side 80 of the controller and engaging the detent piece at the side and the pawl carrying lever passing to the other side around the controller, the pawl engaging the ratchet wheel substantially opposite said pivotal mounting 85 for the levers, and means urging said levers toward the controller.

6. A cylindrical lamp socket including in combination a rotatable controller arranged transversely of the axis of the socket, a detent piece and a ratchet wheel located substantially centrally of the controller and substantially on the diameter of the socket, a detent lever and a pawl carrying lever having a common mounting eccentric to the 95 controller, the detent lever engaging the detent piece at one side and the pawl lever passing around the other side of the controller and the pawl engaging the ratchet wheel substantially opposite said pivotal 100 mounting.

7. A lamp socket including in combination a rotatable controller arranged transversely of the axis of the socket, conducting pieces at each end of the controller, a branch 110 of the circuit at either side of the socket having contacts coöperating with the conducting pieces on the controller to open and close the branches of the circuit, respectively, a ratchet and a detent piece fixed to 115 rotate with the controller and located intermediately the conducting pieces, a pawl carrying lever and a detent lever having a common pivotal mounting eccentric to the controller, the detent lever passing to one side of the controller and engaging the detent piece at the side and the pawl carrying lever passing to the other side around the controller, the pawl engaging the ratchet wheel substantially opposite said pivotal mounting 120 for the levers, and a spring in tension between the detent lever and pawl.

8. A cylindrical lamp socket including in combination two opposed heads, supports between said heads, a rotatable controller 125

- mounted in said supports transversely of the axis of the socket, a conducting piece at each end of the controller, a line contact and a load contact in each branch of the circuit, 5 the line and load contacts in one branch co-operating with one of said conducting pieces on the controller, and the line and load contacts in the other branch of the circuit co-operating with the other contact pieces on 10 said controller, a detent piece and a ratchet fixed to rotate with the controller and located intermediately said conducting pieces, a pawl carrying lever and a detent lever having a common pivotal mounting eccentric to said controller, one of said levers passing to one side of the controller and the other lever passing to the other side of the controller and a spring in tension between 15 said two levers.
- 20 9. A lamp socket including in combination two opposed heads, a plurality of supporting-members connecting said heads, contacts connected to the circuit, a rotatable controller for making and breaking the circuit at said contacts, a ratchet fixed to rotate with said controller, and a pawl carrying lever mounted eccentrically to said controller, one of said members of the supporting structure having means for supporting 25 said controller and said pawl carrying lever.
- 30 10. A lamp socket including in combination two opposed heads, a rotatable controller mounted transversely of the axis of the socket and parallel to said heads, two supports connecting said heads a semi-circumference apart, bearings in said supports for the controller, a ratchet fixed to rotate with said controller and located intermediate its ends, an eccentrically mounted 35 pawl carrying lever co-operating with said ratchet and a pivotal bearing for said lever carried by one of said supports.
- 40 11. A lamp socket including in combination two opposed heads, a rotatable controller, a ratchet fixed to rotate with said controller, an eccentrically mounted pawl carrying lever co-operating with said ratchet, an integral support between said opposed heads, said supports having a bearing for 45 the controller and a bearing for the pawl carrying lever.
- 50 12. A lamp socket including in combination two socket heads, a standard connecting said socket heads, a controller member, a detent, a ratchet, a bearing formed on 55 said standard, a detent lever and a pawl lever mounted on said bearing.
- 60 13. A lamp socket including in combination two opposed heads of insulating material, a controller, actuating mechanism therefor, a pull chain connected to the actuating mechanism, a funnel or bell in which the chain runs, and a support connecting said
- heads and to which said bell is attached, and the actuating mechanism also being journaled on said support. 65
14. A lamp socket including in combination two heads of insulating material spaced apart, two standards connecting said heads and located substantially a diameter apart, 70 a non-cylindrical shaft arranged transversely of the socket and supported and rotating on said standards, two members of insulating material mounted upon said shaft, a detent piece and a ratchet wheel on the shaft between said two members of insulating material, said member, detent and ratchet having non-cylindrical apertures slipping on 75 said shaft so that they all rotate therewith, and a detent and a pawl lever for actuating 80 and controlling the movement of the shaft and the parts carried thereby.
15. A lamp socket including in combination two heads of insulating material spaced apart, two standards connecting said heads 85 and located substantially a diameter apart, a non-cylindrical shaft arranged transversely of the socket and supported and rotating on said standards, two members of insulating material mounted upon said shaft, a detent 90 piece and a ratchet wheel on the shaft between said two members of insulating material, said member, detent and ratchet having non-cylindrical apertures slipping on 95 said shaft so that they all rotate therewith, an arm extending out from one of said standards as a support for a pawl and detent lever, and a pawl lever and a detent lever mounted thereon, substantially centrally of said shaft. 100
16. In a lamp socket a controller member of insulating material, a conducting strip mounted thereon and having two contact pieces for connecting or disconnecting two separated contact points in a circuit, and 105 projections formed on said controller for holding said conducting piece thereon relatively to said contact points.
17. In a lamp socket a cylindrical member of insulating material, a contact piece extending across the end thereof and having two contact pieces lying on the cylindrical part thereof a semi-circumference apart, and projecting portions in said cylindrical member whereby movement of the conducting 110 piece either around or lengthwise of said cylindrical member is prevented. 115
